UNITED STATES PATENT OFFICE.

ROBERT W. SCOTT, OF BOSTON, MASSACHUSETTS, ASSIGNOR TO SCOTT & WILLIAMS, INCORPORATED, OF CAMDEN, NEW JERSEY, A CORPORATION OF NEW JERSEY.

YARN-CHANGING MECHANISM FOR KNITTING MACHINES.

1,178,683.

Specification of Letters of Patent. Patented Apr. 11, 1916.

Application filed September 2, 1914. Serial No. 859,894.

To all whom it may concern:

Be it known that I, ROBERT W. SCOTT, a citizen of the United States, and resident of Boston, in the county of Suffolk and State of Massachusetts, have invented certain new and useful Improvements in Yarn-Changing Mechanism for Knitting Machines, of which the following is a specification.

My invention relates to improvements in 10 yarn feeding mechanism for making split-foot, sectionally spliced and other forms of fabric.

I have illustrated my device in connection with the mechanism shown, described and 15 claimed in my applications Serial No. 746,070, filed February 3, 1913 and Serial No. 845,844, filed June 18, 1914, but it will be evident that the new devices may be applied to other forms of knitting machinery. 20 In my said applications I disclosed a yarn changing and yarn splicing device comprising a series of yarn guides pivoted above and outside of the circle of needles in a circular knitting machine, and a device for 25 moving said yarn guides to change their yarns comprising a series of thrust bars, in direct contact with said yarn guides, and with a pattern cam surface. One of the yarn guides was, for sectional splicing, provided 30 on its under side with a lug against which the nose of its thrust bar takes, to elevate the yarn guide upon movement of said thrust bar laterally.

The present invention provides mechanism 35 for an exchange of yarns during rotary knitting in the same course at a plurality of separated intervals about the knit tube, so operating as to hold the yarn guide about to go out of work in its operative position until after the yarn guide put into work 40 shall have begun to feed a new yarn to the needles. My new devices provide for an exchange of this nature occurring persistently at the same needle wales for course after 45 course, to provide a longitudinally split or sutured fabric, such for instance as will be suitable for a substituted fabric above the heel at the back of a stocking, or for a split foot, which may if desired be provided with 50 a sole of a heavier yarn, or a yarn different in color or kind from the leg and the top thereof. The said devices provide for the above functions without increasing the necessary number of yarn guides, which may 55 also include a yarn guide and means for

sectional splicing, my invention comprising means for the normal operation of the yarn-guides employed for split foot knitting as yarn-changing yarn-guides.

In the accompanying drawings, Figure 1 is a vertical section illustrating the pattern mechanism, the yarn-guides, the stitch-cams and the needle cylinder of a circular knitting machine, as one instance only of my new devices; Fig. 2 is a plan partly in section on the line 2-2 of Fig. 1 illustrating the auxiliary yarn-guide actuating mechanism in plan; Fig. 3 is a diagram plan of the needles showing the course of the yarns for a typical fabric; Fig. 4 is a detail perspective showing one of the adjustable actuating cams.

Referring now to Fig. 1, the machine selected for an illustrative instance comprises a rotary needle cylinder 260 driven by a gear 30 to which cylinder is attached a web-holder bed 295 capable of rotation with respect to the web-holders 290. It will be understood, however, that my invention is not restricted to machines of this type, the devices for performing my new purposes being capable of application without change in their essentials to knitting machines of other types. The bed-plate D on which said needle cylinder rotates carries a standard 401 upon which is pivoted at 552 a latch guard ring carrying a stud 554 upon which a series of yarn guide levers F are journaled to occupy under the influence of springs F^a a normal operative lower position of rest at 556 which their inner ends stand upon a throat plate 559 bridging a gap in the latch ring through which the yarns are given to the needles. The said devices, as shown in Fig. 1, are at the neighborhood of the plane central of a stitch-cam group, which may be of any usual form.

The machine comprises a series of thrust bars 460 guided in a comb 451 attached to a stud 450 projecting from the frame of the machine, the lower beveled ends of said thrust bars being in the path of pattern cams 501, on the surface of a pattern drum 120 intermittently actuated during the operation of the machine, acting to lift the individual thrust bars to remove their yarn guides F upwardly and inwardly out of action. Motions of the pattern drum 120 are, in comparison with the rate of rotation of the needle cylinder 260, relatively infre-

quent. The thrust-bars 460 constitute operating connections individually controlled by the pattern surface 120.

For yarn changing occurring a plurality of times in each course of movement of the selected pair of yarn guides F at shorter intervals, and in time with the passage by the throat plate 559 of a predetermined part of the needles, is provided for.

10 I prefer to employ at the location of the sutures in the fabric short butt needles n^3 , among a series of needles having longer butts n^1 , n^2 , and a top center cam 8 cut away at 10 to secure a higher position of the two 15 or more groups of suture needles n^3 at the yarn guides, the difference in elevation between the suture needles n^3 and the remaining needles aiding the sharp entrance and exit of the yarn on either side of said suture needles. The yarn guides for the split fabric when in their lowermost position deliver their yarns to all of the said needles, when in an intermediate position, deliver their yarn above the heads of all of the needles 20 except the suture needles and when in an upper position, hold the yarn idly above all the needles.

In order to actuate two of the thrust bars, which may be any two, so as to enter and release 30 the yarns of their yarn guides F for the purpose stated, I provide said thrust bars with notches a, capable of being engaged by operating devices now to be described.

35 On the stud 450 and conveniently on a bearing turned on the hub of a stitch-length adjusting lever 281 forming a part of the existing machine, I provide a lever 700, having an indicator arm 701 and an upper arm 40 702. Indicator arm 701 is in the path of cams 522 attached to the surface of drum 120. Said arm 702 is provided with a lug 704 and carries a rigid stud 703 on which rocker levers 710 and 711 are pivoted by 45 means of bores in central parts formed as yokes 712 and 713, each yoke straddling a part of the other, to permit a wide and steady bearing on stud 703 for said rocker levers. Limit screws 715 held by lock-screws 50 716 in lug 704 engage with the lug 707 of lever 710 and with yoke 713 of lever 711, to limit the motion of levers 710 and 711 under the stress of springs 720 held by an adjustable arm 721 in a transverse bore in stud 55 703 by a screw 725. The levers 710, 711 terminate at one end in oppositely facing grooved portions 730, 731, split at b, bored and threaded for clamp screws c, to enable adjustment of bits d, lying respectively in the planes of 60 said thrust bars, with respect to the grooved faces of said portions 730, 731. The other arms 732 and 733 of said levers 710 and 711 terminate in bosses e and f each having a transverse bore for a hardened follower pin g, said 65 pins having rounded ends projecting from

said bosses, and having their lower ends beveled to coöperate with adjustment screws h transversely in said bosses. The screws h carry elongated jam nuts k each of which surrounds a set screw m taking through the boss into engagement with a pin g. Setting up screws m will lock the screws h and pins g simultaneously.

The rounded points of the pins g serve as followers for determining movement of levers 710 and 711 from actuating means comprising adjustable cams 736, 737 carried on the surface of an integral drum 735 at the hub of gear 31 in mesh with gear 30. Drum 735 rotates in unison with the needle-cylinder 260. Cams 736 and 737 are preferably alike, having a concentric surface x, a leading slope y, and a following slope z, slope z terminating over a concentric undercut housing an annular segment 738 of lesser radius slotted at 739 for adjustable attachment by screw 740. The rear edge of segment 738 provides a sharp descent for follower g. Cams 736, 737 are each provided with a flange 741 slotted at 742 for adjustable attachment by screws 743.

The splicing yarn guide F° forming a part of my said machine disclosed and claimed in application Serial No. 845844 as above mentioned, is operated as shown therein by a thrust-bar 460^b having a lug s' in the path of a segmental cam 296 attached to the web-holder bed 295. When said bar 460^b is in the lower position permitted by cam 500 on drum 120, adjustably determined by an eccentric stop 448 contacting with comb 452, cam 296 reacts with lug s' to move bar 460^b laterally against a cam lug F° on yarn guide F° during a part of each revolution of the needle cylinder thus to remove 105 a splicing yarn carried by yarn guide F° from that part of the circle of needles corresponding to cam 296, and feed the said yarn to the remaining needles only. As fully set out in said application, the section of 110 needles so fed may be the short butt needles at the back of the leg of the stocking, including the needles n^2 and n^3 , and the stitch length at said needles may be increased by altering the position of some of the web-holders during feeding of the splicing yarn by adjustment of a cam 312. The splicing yarn ordinarily is a relatively thin 115 yarn, not suitable for either part of the foot and different therefore from the yarns carried by the guides for the leg yarn or the guides F for feeding yarn at the top and bottom of the foot respectively.

The operation of my new device will now be apparent. At the proper time in the knitting of an article, which may be at any desired time, for instance prior to reaching the heel, cam 500 runs from under thrust-bar 460^b, causing yarn-guide F° to feed splicing yarn to needles n^2 , n^3 only during 120

knitting of the ankle. The heel is knit as usual, and thereafter one or both of the bars 460 are lowered by movement of drum 120 and cams 500 and 501, whereupon a cam 522 on the drum 120 passes under the indicator member 701 of the lever 700, rotating the axis 703 from a lower idle position into the position illustrated in Fig. 1, this motion causing the bits *d* to enter the notches *a* of the selected pair of thrust bars, and the followers *g* to come into range of cams 736, 737. The shaft 32, the drum 735 and the cams 736, 737 rotating at the same rate as the needle cylinder 260, an exchange 15 of position of the thrust-bars and of their yarn guides *F* in time with the passage by throat plate 559 of any given part of the needle-circle will now be determined by the rotative position on drum 735 of said cams 20 736, 737 and the adjustment of levers 710, 711. The extent of elevation of the guide *F* thrown out of work will depend on the position of the follower *g* through which it is elevated, while the number of needles embraced by overlapped entering and leaving 25 yarns will be determined by the position of slope *z* of one cam with respect to slope *y* of the other cam. The adjustment is such as to cause a follower *g* reaching the intermediate level of segment 738 to position its 30 yarn guide *F* at an intermediate position causing the yarn of the entering yarn guide to first encounter the leading needle *n*¹, just prior to the similar adjustment of the other 35 yarn guide *F* by slope *y* to cause its yarn to leave the needles at the following needle *n*² of the same group. Passage of segment 738 permits the entering yarn guide to pass to its lowermost position on throat plate 40 559, thus insuring feeding of all the needles *n*¹ or *n*² following the suture needles *n*³.

It will be observed that the system made up of the lever 700 and its attachments is normally held by gravity in a position out 45 of contact with the thrust bars which it operates or with the cam drum 735 and attachments by which it is operated, and that there is no motion of the parts carried by the said lever 700 except when the special 50 structure is to be made. When the lever 700 is in an idle position the thrust bars for the guides *F* are available to be operated by the cams 501 on the drum 120 in their usual manner for changing the yarn at predetermined parts of the fabric.

While I have described the operating connections 460, etc., in one use between the pattern mechanism 120 and knitting instrumentalities such as the yarn-guides *F*, it will be understood that such connections are often employed to operate other knitting instrumentalities, and that my new devices for moving said connections from another actuating device than the said pattern mechanism form a part of my invention inde-

pendently of the use to which movement of the connections 460 may be applied.

I do not herein claim the invention common to this application and my copending applications above mentioned or common to this application and my application Serial No. 851,931, filed July 20, 1914.

What I claim is:

1. In a knitting machine, needle and cam carriers, a plurality of yarn guides, an independent thrust-bar for each of said guides, pattern means for lifting each thrust bar to operate its yarn guide, in combination with actuating means, and devices operated thereby independently to lift one or more of said thrust-bars at predetermined times.

2. In a knitting machine, needles and cam carriers, means to rotate one of said carriers for knitting, a plurality of yarn guides, an independent thrust-bar for each of said guides, pattern means for lifting each thrust-bar to operate its yarn guide, in combination with actuating means rotating in time with said rotary carrier and devices operated thereby independently to lift one or more of said thrust bars at predetermined parts of each rotation of said rotary carrier.

3. In a knitting machine, needle and cam carriers, a plurality of yarn guides, and pattern controlled operating connections for said yarn guides, in combination with actuating means, devices normally out of contact with said connections for operating said connections from said actuating means, and means for placing said devices in operative contact with said connections at predetermined times.

4. In a knitting machine, needle and cam carriers, a plurality of yarn guides, and pattern controlled operating connections for said yarn guides, in combination with actuating means, devices normally out of contact with said connections and said actuating means, and means for placing said devices in contact with said connections and said actuating means to operate said yarn guides from said actuating means at predetermined times.

5. In a knitting machine, needles and cam carriers, means to rotate one of said carriers for knitting, a plurality of yarn guides, an independent pattern controlled operating connection for each of said yarn guides, actuating means rotating in unison with said rotary carrier, and devices movable into contact with each of a plurality of said connections to operate their yarn guides independently from said actuating means at predetermined times.

6. In a knitting machine, needles and cam carriers, means to rotate one of said carriers for knitting, a plurality of yarn guides, an independent pattern controlled operating connection for each of said yarn

guides, actuating means rotating in unison with said rotary carrier, and devices movable into contact with each of a plurality of said connections to operate their yarn guides independently from said actuating means at predetermined parts of each rotation of said rotary carrier.

7. In a knitting machine, a pattern surface and means to move said surface, yarn guides, and connections whereby said pattern surface determines operation and inoperation of said yarn guides, in combination with actuating means, operating devices between said actuating means and said connections and means moving with said pattern surface for rendering said operating device operative or inoperative upon said connections.

8. In a knitting machine having a knitting instrumentality adapted to be controlled at predetermined times and mechanism for controlling it, the combination of an operating connection between said instrumentality and said mechanism, actuating means, an operating device for moving said operating connection from said actuating means, and means for bodily moving said operating device into and out of operative contact with said actuating means and with said operating connection.

9. In a knitting machine having knitting instrumentalities adapted to be operated at predetermined times, and pattern mechanism for operating them, a plurality of operating connections between said instrumentalities and said mechanism, actuating means and operating devices for moving each of said operating connections independently from said actuating means, comprising independent levers, in combination with means for bodily moving said levers into and out of operative contact with said actuating means and with said operating connections at predetermined times.

45 10. In a knitting machine, knitting instru-

mentalities and a plurality of operating connections thereto, pattern devices for directly moving said connections, actuating means, and a series of actuating levers for said connections, in combination with means operated by said pattern devices for bodily moving said levers into and out of contact with said actuating means and with said operating connections at predetermined times.

50 11. In a knitting machine, the combination with needles of means for feeding yarn for tubular knitting, means for feeding an additional yarn for splicing to a section of said needles only, and means for feeding yarns respectively to each of overlapping sections of said needles for split tubular knitting.

55 12. In a knitting machine in combination, needles, independently movable yarn guides, means for operating one of said yarn guides for splicing at one section only of said needles, and means for operating other of said yarn guides to knit respectively at said section and at the remainder of said needles for split tubular knitting.

60 13. In a knitting machine, needles, independently movable yarn guides, means comprising a cam relatively fixed with respect to said needles for rendering one of said yarn guides operative and inoperative for sectional splicing, in combination with means for alternately rendering operative and inoperative other of said yarn guides at the passage of predetermined needles, for split tubular knitting, and means for predetermining the times of operation of said means.

65 In testimony whereof, I have signed my name to this specification in the presence of two subscribing witnesses.

ROBERT W. SCOTT.
